UNITED STATES PATENT OFFICE.

PHINEHAS BALL, OF WORCESTER, MASSACHUSETTS.

ROTARY WATER-METER.

SPECIFICATION forming part of Letters Patent No. 521,493, dated June 19, 1894.

Application filed October 23, 1893. Serial No. 488,864. (No model.)

To all whom it may concern:

Be it known that I, PHINEHAS BALL, a citizen of the United States, residing at Worcester, in the county of Worcester and State of Massachusetts, have invented a new and useful Improvement in Rotary Meters, of which the following, together with the accompanying drawings, is a specification sufficiently full, clear, and exact to enable persons skilled 10 in the art to which this invention appertains to make and use the same.

The objects of my present invention are to provide a rotary meter of simple construction and efficient operation; to improve and 15 perfect various structural details embodied therein, and to provide superior means for controlling the delivery of the fluid upon the rotary piston or measuring wheel in order to impart thereto a motion uniformly proportioned to the quantity of fluid passing through the apparatus. These objects I attain by 20 mechanism constructed and organized for operation as explained in the following description, the particular features of invention 25 claimed being hereinafter definitely specified.

In the drawings, Figure 1 is an exterior end elevation, and Fig. 2 a vertical longitudinal section at line xx , of a rotary meter embodying my invention. (The upper part or register is not herein shown.) Fig. 2¹ is an outline of the valve. Fig. 3 is a plan view, with the top-portion of the case and upper mechanism removed. Fig. 4 is a sectional diagram showing the automatic controlling valve 35 in elevated position, and Fig. 5 is a horizontal section through the valve and its seat.

Certain parts employed in this improved meter, such as an outer casing; a revolving piston or wheel; intermediate reducing gearing; and an indicating register are, broadly 40 considered, common in all rotary meters; hence no special description of such parts is herein given, except in so far as such parts are specially adapted and combined in their particular relation to this invention.

In accordance with my invention the mechanism is preferably embodied in practical form as will now be described in detail.

Referring to parts, A denotes the exterior 45 case or body of the meter, made in suitable form and adapted for properly containing and supporting the operating parts. This case

comprises an upper and lower part, in the latter of which is located the circular wheel-chamber B, and adjacent thereto an upright valve chamber C, separated therefrom by a wall or partition through which is formed the delivery mouth D. The body is provided with the inlet a and outlet a' for the fluid or gas to enter and pass from the meter; said inlet communicating with the valve-chamber C and the outlet communicating with the wheel-chamber B. The upper part A' of the case includes a chamber for the reducing gearing E, and has an extension that closes 55 the top of the valve-chamber. The two parts of the case are connected by bolts or screws in well known manner. The bed-plate E' of the reducing gear-train forms a cap for the wheel-chamber B. An auxiliary chamber or 60 hollowed cavity B² is formed at the bottom of the wheel-chamber having an inwardly directed horizontal annular bridge or border flange b' concentric with the wheel circle and turned level on its top surface. A series of 65 inwardly projecting upright ribs 3 is formed on the body casting A about the chamber B as shown. The inner faces of these projecting ribs are bored or turned to an accurate circle concentric with the surface or circle 70 described by the outer limit of the wheel.

The recesses between the projecting ribs 3 serve the purpose of a complete water packing preventing small volumes of fluid passing 75 without moving the wheel, and also limit the 80 surface on which foreign substances can cling to interfere with the revolution of the wheel.

Within the chamber B there is arranged the rotatable measuring piston or wheel F mounted on a suitable axis or pivot so as to 85 be revolved by the fluid flowing through the mouth D. This measuring wheel consists of a body of hard rubber or other suitable material provided with a series of radially projecting vanes or floats f about its periphery; 90 the ends of which vanes, as the wheel revolves, pass in close proximity to the ribs 3 formed on the interior of the case. The wheel is 95 preferably supported on an adjustable step 4 screwed into a post cast in the base of the meter-body. In this step is inserted the pin 5 on which the wheel-shaft 6 revolves. A beveled seat of special metal, or material which has the property of resisting wear and

abrasion in a high degree, sustains the pin 5 and fits the lower end of the shaft 6, which is correspondingly formed. The height or relative vertical position of the wheel in the case 5 or body can be adjusted by turning the screw-step 4 in or out according to requirements in fitting up, and also to compensate for wear. A loose collar 7 is preferably arranged at the top of the wheel-shaft, fitting the bearing in 10 the plate E'; said collar being free to rotate in the bearing or the shaft to rotate in the collar, thus avoiding liability of sticking or interfering with the free action of the wheel. The wheel-shaft is best made with an internal 15 chamber 8 for containing fine plumbago or other suitable lubricant for the bearing step 4 and pivot 5. A small passage 9 is formed thereinto for the admission of fluid to the chamber to cause the lubricant to settle as 20 fast as required. A pinion attached to the wheel-shaft gears into the first wheel of the intermediate reducing train for transmitting the motion of the wheel B to the register in well known manner.

25 The valve chamber C is of cylindrical form for containing the vertically movable valve controlling the mouth D, through which the fluid passes to the wheel-chamber. The inner surface of the valve-chamber is preferably 30 formed with a series of upright ribs c and a horizontal annular bridge c^2 separates the upper and lower part of the chamber, and their inner surfaces are accurately bored or formed to match the cylinder of the valve; which fits 35 the bored or milled surface between the recesses, and in which surface the mouth D is located. In any instance, if desired, the chamber may be formed with a plain cylindrical inner surface, the recesses being omitted.

40 In my present improvement a single mouth D is used of a definite size controlled automatically by the gravity valve hereinafter described. The location and direction of the mouth are indicated in Figs. 3 and 5. This 45 mouth is proportioned in size to the quantity of water measured by the meter, and hence its size is varied as the size of the meter varies, the position and direction of the mouth in the body are such as will give a uniform direction 50 of the current passing therethrough, and afford the most effective impact of the current upon the vanes of the measuring-wheel. It is formed with reference to directing or guiding the fluid to impinge upon the vanes of the 55 wheel in one constant path, whether the flow is in large or small stream. This feature is important as it effects proportional uniformity of action in the movement of the meter. By the use of a proper templet the drilling and 60 forming of the mouth can in practice be effected with uniformity, as to the size and direction, in the various meters.

The valve I is made in the form indicated, 65 as a cylindrical body with a vertical axis, and of definite weight; that is, not subject to variation in its resistance; its upper portion or head fitting the valve-chamber with a good

working fit, sufficiently free to move easily up and down; the design being not to have too much space around it to occasion leakage, 70 but enough to maintain easy and free working for a long time in practical use. The lower part I' of the valve is best made of less diameter than the upper part or head. The valve has a narrow annular groove J extending 75 around it horizontally near the lower part of its head, which groove serves as a port to the mouth D. The height of the valve body is such that the groove J will not fall below the lower edge of the mouth when the lower 80 end of the valve rests upon the stop 12 at the bottom of the valve-chamber, as when in its depressed or inactive position. This groove provides a port always open, and when forming the smallest port with the mouth its 85 opening is such that the smallest stream of fluid passing through the mouth must acquire a velocity sufficient to move the wheel F. It also serves as a means of draining the service pipes and meter, to prevent freezing 90 or in case of needed repairs, when the service is shut off at the inlet head. Suitable openings or ports n are formed vertically through the flange i of the valve below the annular groove J; the object of these ports 95 being to afford passage for the fluid from the inlet-chamber into the annular groove and through the mouth passage, when the valve-head is surrounded by the body shell at its closed position, so that sufficient fluid is 100 passed through the ports and the mouth, and with sufficient velocity to cause rotary movement of the measuring-wheel. The recesses c' may in some instances be made to serve for admitting fluid into the groove J from 105 the inlet chamber. The valve is preferably hollow or formed with a cavity m to facilitate the adjustment of its weight by adding shot or other substances within said cavity to the desired degree; which substance may then be fixed in place by melted sealing wax or other fixative poured into the hollow.

A small port or aperture 10 is made through the wall or partition from the upper part of the valve-chamber into the wheel-chamber; 115 communicating from the space above the valve with the outlet side of the meter, and as the action of the valve in covering the mouth- 120 passage D effects a variation of pressure between the chambers which is always less in the wheel-chamber B than in the inlet-chamber C, the valve is forced to rise vertically, the fluid in the space above the valve being forced out or permitted to escape through the aperture 10, so that the valve can freely perform its 125 designed action in manner as set forth. The ribs c keep the alignment of the valve in its up and down movement, and the recesses c' between the ribs reduce the surface exposed to the valve where matter or substances of 130 various kinds can wedge in and impede the proper movement of the valve. The cavity or auxiliary sub-chamber B² with the inwardly projecting ledge b' at the bottom level of said

wheel chamber, affords a water pack beneath the wheel, which tends to regulate or cause a steady movement; giving a more accurate measurement under varying quantities of delivery; and insures greater uniformity and reliability in the operation of the meter. The ledge b' extends under the vanes f nearly to the face of the cylindrical body of the wheel and deflects therefrom currents that might otherwise tend to interfere with the proper wheel action.

In the operation, the valve is raised responsive to the flowage, it being actuated wholly by the inlet pressure of the fluid and thus automatically controls the delivery mouth passage by reason of the side of the valve head sliding past the mouth D and thereby increasing or reducing the opening causing the measuring-wheel to act with and proportionally to the quantity of fluid delivered. When a large quantity of fluid is called for, by free opening of the exit the increase or variation of pressure will lift or force the valve higher in the chamber, (as in Fig. 4) uncovering a greater portion of the mouth D and giving more delivery. The mouth being thus opened and closed by the automatic rise and fall of the valve, proportionally with the variation of pressures in the wheel-chamber, as compared with that in the inlet-chamber, regulates the current so as to give a forceful flow for the fluid that will cause the measuring-wheel F to rotate in unison therewith and move the register mechanism to a degree corresponding to the quantity of fluid passing through the meter. When all service pipes are closed the valve falls within the chamber until it rests on the stop 12 in the position shown on Fig. 2.

40 The valves I are made of uniform weight for a given size of meter, and vary in size proportionally as the size of the meter varies; or as the area of the valve-chamber is made larger or smaller. This construction of the valve with the groove insures a small section of the mouth always open as a delivery port, hence if the valve should stick an open port would result at any vertical position, and insure constant delivery of fluid.

50 What I claim, and desire to secure by Letters Patent, is—

1. In a rotary meter, the body-casing provided with the upright valve-chamber and a wheel-chamber, inlet and outlet passages respectively communicating with said chambers, and a definite delivery-mouth between said chambers disposed for directing the current of fluid upon the wheel, in the manner set forth, in combination with the rotatable measuring-wheel, comprising the central body having a series of radial vanes; and the vertically-movable unattached valve of invariable weight disposed within said valve-chamber, its cylindrical head acting as a cut-off across said mouth and operating by gravity and the force of the inlet fluid, as set forth.

2. In combination, the body-casing, the reg-

ister-operating gearing, the measuring-wheel consisting of a central body with projecting radial wings rotating on a vertical axis with- 70 in the wheel-chamber, the upright inlet-valve-chamber having the definite mouth for delivering the fluid therefrom upon said wheel, the vertically moving gravity valve fitting within said valve-chamber and sliding as 75 a cut-off across said mouth, for increasing or diminishing its passage automatically, as the flowage is increased or diminished, said valve having an annular pass-way-groove therein which partially uncovers said delivery mouth 80 when the valve is depressed, substantially as shown and described.

3. In a rotary meter, in combination with the body casing provided with the wheel-chamber, the valve-chamber and the delivery 85 mouth arranged in the side thereof for directing the impelling current; of an automatic controlling valve having a narrow circumferential groove about its cylindrical face, that aligns with and partially uncovers said de- 90 livery mouth when the valve is depressed or at inactive position, as set forth.

4. In a rotary meter, as described, the meter casing containing the wheel-chamber and the inlet or valve-chamber having the definite 95 mouth for directing the fluid upon the measuring wheel and provided with a small aperture or opening from the upper part of said valve-chamber to the outlet or wheel-chamber, in combination with the measuring wheel, 100 the gravity-valve of definite weight for controlling said mouth, having a narrow annular groove around the lower part of its head, and a dependent end or stop that arrests downward action of the valve while its groove 105 is in conjunction with the mouth, all substan- tially as set forth.

5. The gravity-valve having the annular groove formed around its seating head and provided with a series of vertical ports leading from the under side of the head into said groove, as set forth, in combination with the upright inlet-chamber, the delivery mouth controlled by said valve, and the rotary measuring-wheel in a fluid meter, for the purpose 110 115 set forth.

6. In a rotary meter, the meter casing having its wheel-chamber B , provided with the bottom-cavity or sub-chamber B^2 opening into said wheel-chamber, and the annular inwardly projecting flange or ledge b' partially separating said chambers; in combination with the rotatable wheel F disposed within said wheel-chamber with its vanes extending over said ledge, substantially as and for the 120 125 purpose set forth.

7. In a fluid meter having an operating wheel or fan, and a fixed mouth for directing the fluid upon said wheel, the combination with said mouth and the inlet thereto, of the 130 closed valve-chamber, its interior fitted with ribs c , annular bridge c^2 with cylindrically turned inner surface and foot stop 12, and an automatically actuated valve, its head fitted

to said inner surface and moving across said mouth to open or close its passage, said valve having its lower end adapted for resting upon said stop when the valve is inactive or depressed to its lowest position, for the purposes set forth.

8. The meter body or casing internally provided with narrow inwardly projecting ribs 3, in combination with the measuring - wheel 10 having outwardly projecting vanes *f*, the ends

of which match in circle and contour the inner faces of said ribs and pass, without contact, in adjacent proximity to said ribs as the wheel rotates, for the purpose set forth.

Witness my hand this 18th day of October, 15
A. D. 1893.
